UNITED STATES PATENT OFFICE.

JOSEPH W. NETHERY, OF INDIANAPOLIS, INDIANA, ASSIGNOR TO THE NETHERY HYDRAULIC VALVE COMPANY, OF INDIANAPOLIS, INDIANA, A CORPORATION OF NEW JERSEY.

VALVE.

SPECIFICATION forming part of Letters Patent No. 747,468, dated December 22, 1903.

Application filed November 8, 1901. Serial No. 81,545. (No model.)

To all whom it may concern:

Be it known that I, JOSEPH W. NETHERY, a citizen of the United States, residing at Indianapolis, in the county of Marion and State 5 of Indiana, have invented certain new and useful Improvements in Valves, of which the following is a specification.

This invention relates to that variety of valves or faucets which when opened will after 10 a predetermined flow of fluid automatically close.

A valve embodying said invention will be first fully described and the novel features thereof then pointed out in the claims.

15 Referring to the accompanying drawings, which are made a part hereof, and on which similar reference characters indicate similar parts, Figure 1 is a central vertical sectional view of a valve or faucet embodying my said 20 invention, the main valve and the starting-valve being both shown in closed position; Fig. 2, a similar view, except that the starting-valve has been raised, the parts being shown in the positions they occupy just before the main valve starts to open; and Figs. 25 3 and 4, horizontal sectional views looking downwardly from the dotted lines 3 and 4, respectively, in Fig. 1.

Assuming this valve to be arranged in the 30 ordinary way for controlling fluid, such as water, the fluid enters from the side through the ingress-opening at 5, as indicated by the arrow at that point, and passes out through the main-valve seat to the egress pipe or opening 35 6, as indicated by the arrow at that point. The body or shell 7 of the valve contains the main-valve seat 8 and is provided with a removable cap 9. This valve is in the main preferably in the form of a cylinder. Within 40 the chamber is the main-valve structure, consisting of the main valve 10, a hollow stem 11, and a piston-head 12. Said piston-head is at the opposite end of the stem from the main valve and is of larger diameter than 45 said main valve, so that the valve and the piston-head present differential surface areas to the pressure of the incoming fluid. The upper edge of the piston-head extends to above the ingress-opening, and thus divides the cylindrical chamber into two compartments,

one below the piston-head, into which the incoming fluid immediately discharges, and the other above said piston-head, to which ingress is had by a small opening, as by the perforation *p*. Said piston-head is shown as cup-shaped in form, the cup portion being interiorly screw-threaded, with a gasket 13 in the bottom of the cup, where it is held by an annular screw-threaded follower 14. Said gasket forms a seat for the starting-valve 15, 60 which is formed or carried on the stem 16, which extends to the outside of the main-valve structure and also extends down into the tubular opening through the main-valve stem 11, and preferably carries upon its lower 65 end a star-shaped guide 17, by which it is guided in its movements, while the passage of fluid is not prevented. Upon the upper end of said stem is a knob or button 18, by means of which the starting-valve is manipulated by the operator. This starting-valve 70 15 is disk-like in form and its exposed surface is upward when said valve is closed, so that the pressure of the fluid in the compartment in which said valve is contained holds said 75 valve with considerable force onto its seat and prevents accidental displacement.

As above stated, the main valve 10 is smaller in diameter (and consequently in area) than the piston-head 12. It is adapted to 80 rest upon the valve-seat 8 when closed and is guided in opening by the wings 20, as shown, and as will be readily understood.

The operation of my improved valve is as follows: The main valve being closed, the 85 starting-valve 15 is raised from the position shown in Fig. 1 to the position shown in Fig. 2. This leaves a free passage for the fluid which has accumulated in the compartment above the piston-head out through the discharge-way formed by the orifice in the tubular valve-stem 11, and thus relieves the pressure in said compartment. The pressure of the incoming fluid (being greater upon the piston-head than upon the main valve by reason of its larger area) forces the main-valve structure up, thus opening the main valve 90 and permitting the incoming fluid to flow through. As the main-valve structure reaches its uppermost position the gasket 13 in the 100

piston-head 12, which forms the seat for the starting-valve 15, comes against the starting-valve, thus seating it and stopping the flow through the opening in the valve-stem 11. 5 The small quantity of fluid which is entering through the perforation *p* presently fills the compartment of the chamber above the piston-head, equalizing the pressure on the two sides of the piston-head and permitting the pressure on the main valve 10 to force it down onto its seat. Said main-valve structure is accompanied in this movement by the starting-valve, which is kept in contact with its seat on said main-valve structure, as above stated. The time which this last-named operation occupies, and consequently the quantity of fluid which shall be discharged at one operation of the valve, is determined by adjusting the effective size of the perforation *p*, which may be done by means of the slotted screw 21, which is placed therein.

Having thus fully described my said invention, what I claim as new, and desire to secure by Letters Patent, is—

25 1. The combination, in a piston-valve, of a shell or body containing a cylindrical chamber and having a main-valve seat at its discharge end and also having an ingress-opening at one side between the valve-seat and the opposite end, a main-valve structure situated in said chamber composed of a hollow valve-stem with the main valve upon one end thereof and a piston - head upon the other, said piston-head extending to above the ingress-opening and dividing the chamber into two compartments, a passage from the ingress to the upper compartment, a starting-valve arranged in the upper compartment and having its valve-seat on the upper surface of the piston-head, a valve-stem carrying said starting-valve and extending through the head of the main shell or body to the outside where it can be reached by the operator and also extending down through said valve

into the orifice in the main-valve stem whereby it is guided, substantially as shown and described. 45

2. The combination, in a piston-valve, of a main-valve structure having an upper and a lower compartment, a central discharge-orifice leading from the upper compartment of the valve-chamber down through to a point adjacent to the main egress-opening, and a starting-valve stem extending up through the head of the main shell or body to the outside, 55 and a starting-valve carried thereby and situated in said upper compartment and adapted to close said orifice, said starting-valve being in the form of a disk at its lower or operative end which presents a surface to the action of the fluid in said compartment when filled, whereby the pressure of such fluid causes said starting-valve to remain seated until forcibly opened, substantially as shown and described. 60

3. The combination, in a piston-valve, the main-valve structure wherein contains a discharge-orifice leading from the upper compartment down through said structure to a point adjacent to the main egress-opening, 70 of an auxiliary or starting valve situated in said upper compartment, and a valve-stem carrying said starting-valve, the lower end of said stem passing down into the discharge-orifice in the main-valve structure where it 75 is provided with a guide for controlling its movement, and the upper end passing up through a suitable stuffing-box to the outside where it can be reached for operating said starting-valve, substantially as set forth. 80

In witness whereof I have hereunto set my hand and seal, at Indianapolis, Indiana, this 10th day of October, A. D. 1901.

JOSEPH W. NETHERY. [L. s.]
